UNITED STATES PATENT OFFICE.

JOHN CHRISTIE, OF NORTH CARLTON, AND ALEXANDER R. LANG, OF ELSTERNWICK, VICTORIA, AUSTRALIA.

FORM FOR MOLDING CONCRETE AND LIKE STRUCTURES.

Application filed October 10, 1922. Serial No. 593,562.

To all whom it may concern:

Be it known that we, JOHN CHRISTIE, a subject of the King of Great Britain and Ireland, and a resident of the postal district of North Carlton, a suburb of the city of Melbourne, in the county of Bourke, State of Victoria, Commonwealth of Australia (whose post-office address is 533 Lygon Street, in the said postal district of 5 North Carlton), and ALEXANDER RICHARD LANG, a subject of the King of Great Britain and Ireland, and a resident of the postal district of Elsternwick, a suburb of the city of Melbourne, in the county of Bourke, 10 State of Victoria, Commonwealth of Australia (whose post-office address is 98 Orrong Road, in the said postal district of Elsternwick), have invented a certain new and useful Improved Form for Molding 15 Concrete and like Structures, of which the following is a specification.

This invention relates to forms for molding structures of concrete or like material and its object is to provide a new type of 20 collapsible form of a portable nature and which may be easily converted to any desired shape and may be readily and minutely adjusted in length at any desired point in the mold wall.

25 The invention is particularly suitable for the molding of concrete buildings in situ but is also applicable to the molding of concrete pipes, slabs, sewer channels and various other articles of a pre-cast nature.

30 By the invention a great amount of time, labor and material involved in erecting and dismantling the usual wooden forms is saved whilst at the same time the invention is capable of molding curves, cornices, 35 fillets, angles and various other intricate or irregular shapes which have hitherto been impracticable or extremely difficult to negotiate with the forms at present in use.

Moreover a single form or set of forms in 40 accordance with the invention may be used repeatedly in the molding of structures of various shapes and sizes by mere manipulation of the flexible form as hereinafter described. The invention also has the distinct advantage of being readily collapsed 45 into a very small space for transport and storage purposes.

The invention consists briefly in a series of substantially parallel metal or other suitable slats or bars preferably of approximately right-angled or V shape in cross section to thus provide two sides in different planes, these slats or bars being pivotally connected together to thereby constitute a flexible chain-like form which may be readily converted to any desired shape. Preferably the two side members or ribs formed by the angle section of each slat are of relatively different widths so that by turning one or more of the slats or bars to bring the narrower or wider side thereof into use the chain-like form may be respectively shortened or lengthened in accordance with certain requirements. A minute adjustment of the length and shape of the flexible form may thus be readily obtained at any desired point in the wall of the mold.

The flexible chain-like forms in accordance with the invention may be employed throughout a mold wall or only where required to produce curves, angles or other special shapes. The straight or plain portions of the structure may then be molded by ordinary sheet metal or other suitable forms.

The following description is directed to a suitable practical embodiment of the invention but it is to be distinctly understood that various alterations, modifications and additions may be incorporated in the apparatus without departing from the spirit and scope of the invention as defined by the appended claims.

Referring to the drawings which form part of this specification:

Figure 1 is a part sectional view of a portion of the improved collapsible form looked at from the ends of the parallel slats or bars.

Figure 2 is a cross section of one of the slats or bars seen in Figure 1.

Figure 3 is a side elevation looking in the direction of the arrow in Figure 1, parts being broken away for convenience of illustration.

Figure 4 is a transverse section taken through the wall of a building and showing the improved form in position on opposite sides of the wall. Parts are broken away

and omitted for convenience of illustration.

Figure 5 is a detail view of a suitable clamping device for use in holding together 5 the forms at opposite sides of a wall.

Figure 6 is a perspective view of a tie piece or strap which may also be employed to hold together the forms at opposite sides of a wall.

10 Figure 7 is a perspective view of one of the connecting links by which the parallel slats or bars are flexibly connected together.

Figure 8 is a perspective detail view of a fastening device which may be employed 15 to attach the improved forms to ordinary forms or for like purposes.

Figure 9 is an external side elevation showing the junction of the improved form with an ordinary form and illustrating how 20 the fastening device seen in Figure 8 may be employed.

Figure 10 is a diagrammatic plan showing 25 the invention in position to mold the curved portion of a wall in conjunction with ordinary or plain forms for molding the straight parts thereof. The concrete material is indicated by the cross hatching on the upper side of the figure.

30 Figure 11 is an end view illustrating how the invention may be applied to the formation of arches and the like.

Figure 12 is a side view of Figure 11.

The invention comprises a plurality of substantially parallel adjoining slats or 35 bars of any desired length. These slats are preferably constructed of light but strong metal of approximately right angled or V shape in cross section, thus providing each slat or bar with two longitudinal or 40 vertical side members 2 and 3 disposed in different relative planes. The side members 2 and 3 are preferably of relatively different widths in cross section as shown and either of said side members is adapted 45 to form part of the mold wall according to the attitude of the respective slat, the difference in width of the two side members permitting of the extension or contraction 50 of the length of the form or mold wall to suit requirements.

The slats are pivotally connected together preferably at their ends by connecting links 4 or the like whereby the chain of slats or bars may be converted into any 55 desired shape. Said links are provided at each end with holes 6 which are preferably elongated in the direction of the length of the links and are adapted to accommodate connecting pins 7 and axially coinciding 60 locking screws 8 which extend lengthwise of the slats and are adapted to connect same pivotally together and also form tensioning rods which extend from end to end of the slats so that by tightening on said 65 screws the slats may be locked rigidly to-

gether against the links when the chain form has been arranged in the desired shape.

End members or webs 11 preferably extend across the opposite ends of the slats, these end members being provided with holes 12 coinciding the holes 6 in the links and also adapted to accommodate the aforesaid connecting pins and screws 8. The latter may be provided with squared heads 13, slots or the like for turning and their inner ends may screw into threaded holes 14 in stationary blocks or nuts 16 accommodated between the side members 2 and 3 of the slats adjacent the ends thereof as shown. These blocks or nuts serve to couple the pins 7 and screws 8 together so as to form continuous tensioning rods as aforesaid whereby the slats may be locked from one end by tightening on the locking screws. The blocks or nuts 16 also positively prevent the slats turning in relation to their connecting pins when the latter are contracted upon the links 4.

By the above means the slats or bars are flexibly connected together and by merely slackening the requisite locking screws 8 any desired slat or slats may be reversed or turned about the axis of its connecting pin to thereby bring either its wide or narrow side member into position to form the mold wall as desired. The slat or slats may be then locked by tightening on the locking screws and the flush outer faces 17 of the slat sides then form a continuous mold wall it being evident that the holes 12 in the slat ends are disposed at an equal distance from both side members 2 and 3 as seen in Figure 2 so that the outer faces 17 thereof will lie flush with each other as in Figure 1 irrespective of which particular side member is in use. By reason of the elongated holes 6 in the links the parallel slats or bars may be moved towards or from each other to take up or extend the length of the chain in accordance with the turning of the slat or slats. By the same means slight openings or slits may be left between the slats to permit of the exudation of surplus moisture from the concrete.

At suitable intervals in the length of the chain-form the links may be provided with lugs 18 having rectangular or other suitable openings 19 to receive the opposite ends 21 of suitable clamping devices 22 which are adapted to bridge the space 23 between the inner and outer forms of a wall or the like and hold said forms together in proper spaced relationship. Said clamping devices may each comprise two relatively telescopic members adjustably locked together by a set screw 24 as in Figure 5 and provided if desired with a handle 26.

As an example of the use of the apparatus in constructing a wall the chain forms are

arranged in the desired relative positions with the parallel slats or bars extending vertically or otherwise according to circumstances, the forms being held together in desired position by the clamps 22 and by tie pieces or straps 27 extending transversely between the forms at the upper and lower ends of the slats as in Figure 4. These tie pieces are preferably provided near their ends with holes 28 to accommodate the connecting pins 7 and they may be tapered to permit of easy withdrawal from the wall after molding. When one portion of the wall has been thus erected in the molding space 23 a further section may be molded by additional forms in accordance with the invention or in the case of straight walls plain sheet metal or other suitable forms 29 may be employed whilst the improved collapsible forms are used only at corners, angles and other desired points. In the above manner the molding of the wall may be completed for a certain height and the forms at the starting point may then be removed and raised to form another tier or higher section of the wall, or in the event of the first section of the wall not having completely set the forms may be left thereon and additional forms placed in superimposed position on the lower forms as in Figure 4. The building up of the wall may be thus continued, the superimposed form units being united if desired by extended screws or connecting pins 31 which pass upwardly through the coinciding holes 6 and 12 in the aforesaid links and the webs or end members 11 of the slats thereby forming in conjunction with the screws 8 and units 16 continuous tensioning rods which extend throughout the height of the superimposed forms and permit the slats to be locked together as before mentioned.

Air spaces or cavities may be formed in the wall or structure by means of collapsible cores constructed from a chain-form in accordance with the invention. These cores may be readily removed after molding and used as external forms or otherwise as desired.

If desired the slats may be telescopic or adjustable in their length so that the height, or width of the chain of slats may be adjusted in addition to the adjustability of its length by the turning of the slats about the axis of their connecting pins and adjustment of the latter in the elongated holes 6 as aforesaid.

To attach the improved forms to the ordinary or plain forms 29 special fastening devices such as seen in Figure 8 may be employed. These fasteners are constructed of wire or the like and comprise a helically coiled portion 32 similar to a corkscrew, and a handle or finger portion 33 by which the coiled part 32 may be screwed into

coinciding holes 34 and 36 in adjoining parts of the chain form and the ordinary form respectively. Such coinciding holes may pass, for instance, through one of the side members 2 and 3 of the slats and the adjacent edge portion or frame 37 of the plain sheet metal form 29 as seen in Figure 9.

In the formation of arches and the like the improved form may be supported by radius rods or the like indicated at 38 in Figures 11 and 12. These radius rods may be telescopic or adjustable in length, set screws 39 being provided for the purpose. The outer ends of the rods 38 may be accommodated by the openings 19 of the lugs 18 on the links whilst the inner ends of said rods may rest in sockets or the like 41 carried by cheeks or supports 42. These supports may be held in opposite alignment by a cross bar 43 and may rest on any convenient member of the building or structure. It will be evident that owing to the adjustability of the radius rods 38 the chain form may be set to any desired contour and by tightening on the set screws 39 and the locking screws 8 the slats of the form may be locked rigidly in the desired position to form the mold. It will be seen that the time, labour and material involved in the erection and dismantling of the usual wooden forms for arches and the like is thus eliminated.

Having now described our invention what we claim as new and desire to secure by Letters Patent is:—

1. A collapsible form for molding concrete and like structures comprising a series of substantially parallel slats or bars, links flexibly uniting said slats, said links having holes therethrough which are elongated in the direction of the length of the links and connecting pins passing through said elongated holes whereby the slats are connected and may be adjusted lengthwise of the links for the purpose set forth.

2. A collapsible form for molding concrete and like structures comprising a series of substantially parallel slats or bars, links and connecting pins pivotally connecting said slats together, said connecting pins being disposed lengthwise of the slats and adapted to form tensioning rods whereby the links may be locked against pivotal movement for the purpose set forth.

3. A collapsible form for molding concrete and like structures comprising a series of substantially parallel slats or bars, links connecting said slats together, connecting pins pivotally attaching the slats to the links and locking screws extending coaxially of the connecting pins at the ends thereof and adapted to contract the links against the ends of the slats for the purpose set forth.

4. A collapsible form for molding con-

crete and like structures comprising a series of substantially parallel slats or bars, links and connecting pins pivotally uniting the slats and locking screws passing through coinciding holes in the links and the end portions of the slats, said screws being provided with turning heads adapted to press against the links for the purpose set forth.

5. A collapsible form for molding concrete and like structures comprising a series of substantially parallel slats or bars arranged in juxtaposition and pivotally connected together, said slats being individually provided with a plurality of sides disposed in different planes and either of which sides

10 may be brought into operative position to form the mold wall by turning the slats about their pivots for the purpose set forth.

6. A collapsible form for molding concrete and like structures comprising a series of substantially parallel slats or bars arranged in juxtaposition and pivotally connected together said slats being of substantially right angled shape in cross sec-

15 tion thereby forming two side members in different planes to each slat, the respective side members being of different widths for the purpose specified.

7. A collapsible form for molding concrete and like structures comprising a series of substantially parallel slats or bars of angular shape in cross section, links and connecting pins pivotally uniting said slats, internally threaded blocks or units disposed on the connecting pins and between the angular members of the respective slats and locking screws passing through the links and into said units whereby the links may be contracted against the ends of the slats and the latter are prevented from turning in relation to their connecting pins substantially as described.

8. A collapsible form for molding concrete and like structures comprising a series of substantially parallel slats or bars of substantially right angled shape in cross section, thus providing each slat with two side members disposed in different planes,

webs extending between said side members at the ends of the slats, links flexibly connecting the slats together at their ends and connecting pins passing through coinciding holes in said webs and links for the purpose set forth.

9. A collapsible form for molding concrete and like structures comprising a chain of substantially parallel slats or bars arranged in juxtaposition, and links flexibly connecting said slats together at their ends certain of said links having lugs projecting sidewardly therefrom and said openings formed through said lugs substantially as and for the purpose set forth.

10. A collapsible form for molding concrete and like structures comprising a series of substantially parallel slats or bars arranged in juxtaposition and pivotally connected together, in combination with a socket support and radius rods each being adjustable and adapted to be connected at their outer ends to said collapsible form to support the latter in position for the formation of arches and at their inner ends connected to said socket support substantially as described.

11. An improved collapsible form for molding concrete and like structures consisting in the combination of a series of substantially parallel slats or bars of angular shape in cross section, connecting links extending between the adjoining ends of the slats and connecting pins and locking screws adapted to pass through elongated holes in said links or slat ends and to form tensioning rods which extend from end to end of the slats whereby the latter may be pivotally or bodily adjusted in relation to each other and locked in desired relative positions by manipulation of said locking screws for the purpose specified.

In testimony whereof we affix our signatures.

J. CHRISTIE.
